UNITED STATES PATENT OFFICE.

DOMINICK ROHEN, OF EVART, MICHIGAN.

PUMP-OPERATING APPARATUS.

1,392,224.

Specification of Letters Patent. Patented Sept. 27, 1921.

Application filed January 13, 1921. Serial No. 436,942.

To all whom it may concern:

Be it known that I, DOMINICK ROHEN, a citizen of the United States, residing at Evart, in the county of Osceola and State 5 of Michigan, have invented certain new and useful Improvements in a Pump-Operating Apparatus, of which the following is a specification.

This invention relates to pumps, more particularly to devices of this character for use in deep wells, or in relatively deep pits above the source of supply, and has for one of its objects to provide a simply constructed apparatus whereby the parts which are liable 15 to deteriorate by rust, wear, and the like, may be detached, repaired or removed and replaced without the necessity for the operator descending into the pit or well.

With these and other objects in view, the 20 invention consists in certain novel features of construction as hereinafter shown and described and then specifically pointed out in the claims, and in the drawings illustrative of the preferred embodiment of the invention.

Figure 1 is a side elevation of the improved apparatus.

Fig. 2 is an enlarged sectional detail of a portion of the three-way chamber or casing 30 and the mechanism for controlling the cut off, and the drainage, to prevent freezing.

Fig. 3 is an enlarged sectional detail of another portion of the three-way chamber and a portion of the pump rod and the suction chamber.

Fig. 4 is a plan view of the three-way chamber.

Fig. 5 is a transverse section of the three-way chamber.

Fig. 6 is a plan view of the compression plate whereby the parts are detachably coupled to the three-way chamber.

Fig. 7 is a sectional detail of the devices whereby the parts are detachably coupled to 45 the three-way chamber.

Fig. 8 is a detached perspective view, enlarged, of the supporting plate for the parts associated with the three-way chamber.

Fig. 9 is a section of the member shown in 50 Fig. 8 together with portions of the suction pipe, the pump rod casing, the discharge or outflow pipe and casing for the cutoff and drainage controlling rod.

The improved apparatus includes a support or platform of suitable construction,

for instance the closure to the pit or well in which the pump is located, and represented conventionally at 10.

Bearing upon the platform 10 is a holding member or support comprising a base portion 11 having three bosses or hubs 12, 13 and 14 directed upwardly therefrom, and a central opening surrounded by a depending flange 15.

Rising from the plate 11 are ears or lugs 16 having set-screws 17 tapped therethrough.

A pipe 18 extends through the central opening in the member 11, and is supported therein by the set-screws 17, as shown in Figs. 1, 6 and 7.

Located within the pit or well and below the support 10 and likewise below the frost line, is a hollow chamber or casing represented as a whole at 19, and divided internally by vertical partitions 20 and 21 into three compartments 22, 23 and 24. A relatively large opening 20' is formed in the partition 20.

The suction pipe or conduit 25 is tapped into the bottom of the casing 19 and communicates with the compartment 23.

Formed in the top of the casing 19 in vertical alignment with the suction pipe 25, is an opening surrounded by a flange 26, and into this opening and its flange a tubular cage or pipe 27 is stepped and provided with a stop flange 28 to limit its downward movement. A packing 29 is interposed between the flanges 26 and 28 to render the joint water tight.

Rigidly supported by any suitable means within the cage 27 is a wear sleeve 30, preferably of brass, or the like.

The members 27 and 30 may be of any suitable length, but the member 27 will generally be about seventeen inches long.

Attached to the upper end of the member 27 is a reducing sleeve or collar 31, and tapped into the upper end of the reducing sleeve is a guide pipe 32.

A jam nut 33 is threaded upon the pipe 32 and bears upon the reducing sleeve to prevent looseness between the parts.

At its upper end the pipe 32 extends through the opening of the boss 14, and terminates a short distance above the same, as shown in Figs. 1 and 7.

Bearing upon the upper elevated end of the pipe 32 is a plate 34, the latter having an opening corresponding to the bore of 110

the pipe 32 and provided with a stop flange 35 to prevent lateral displacement.

The plate 35 is extended at opposite sides of its opening and the extensions slotted to receive L-shaped clamp bolts 36 with the lower ends seated in sockets in the boss 14 and the upper ends provided with clamp nuts 37. By this means the members 27, 31 and 32 are firmly coupled to the casing 19, and at the same time easily detachable by merely loosening the nuts 37 and detaching the bolts 36.

The opening in the boss 14 will be sufficiently large to permit the reducing sleeve 31 and the flange 28 to pass when the member 34 and bolts 36 are released and moved upwardly.

The operating rod of the pump is represented at 38 and passes through the pipes 32, 27 and 25 and likewise through the wear sleeve 30 and compartment 24 of the casing 19.

Attached to the rod 38 and operative in the sleeve 30, is a plunger 39 including a downwardly directed packing member 40 of leather or the like. The main discharge or conductor member is represented as a whole at 41 and extends loosely through the opening in the boss 13 of the member 11, and is tapped into the top of the casing 19 and communicates with the compartment 24.

Tapped into the bottom of the casing 19 and communicating with the compartment 22 is a nipple 42, and connected by a coupling 43 to the lower end of the nipple is an elbow 44 into which a waste pipe 45 is connected.

Tapped into the upper end of the nipple 42 is a sleeve 46, having a valve seat at its upper end.

Formed in the top of the casing 19 is an opening surrounded by an outer flange 47 and an inner flange 48, the latter being tapered internally, as shown in Fig. 2.

Fitting within the tapered flange 48 is a correspondingly tapered sleeve 49, and threaded upon this latter sleeve is a tubular member 50, similar to the member 27, and having a stop flange 51 and packing 52 similar to the flange 28 and packing 29 of the member 27.

Rigidly supported by any suitable means within the member 50 is a wear sleeve 53 preferably of brass or the like.

Attached to the upper end of the member 50 is a reducing sleeve 54 into whose upper end a guide pipe 55 is tapped and supported by a jam nut 56 similar to the like members 31, 32 and 33 associated with the member 27.

At its upper end the pipe 50 extends through the opening of the boss 12 and terminates a short distance above the same, as shown in Fig. 1.

Bearing upon the upper end of the pipe 55 is a plate 57 and coupled to the boss 12 by

L-bolts 58 in substantially the same manner as the plate 34 is secured.

By this means the members 49, 50 and 55 are detachably coupled to the casing 19 and may be removed bodily by merely releasing the bolts 58.

The opening of the boss 12 is large enough to permit the reducing sleeve 54 and flange 51 to pass, as will be obvious.

Extending through the pipes 50 and 55 and the sleeve 49 is a rod 59, and attached to the lower end of the rod is a double faced valve, formed preferably of an intermediate metal disk 60 and leather bearings or packings 61, 62 at each side. The two faced valve is adapted to be seated alternately upon the members 46 and 49, and will be small enough in diameter to pass upwardly through the flange 48 when drawn upwardly with the member 50 and its attachments. Attached to the rod 59 and operating in the wear member 53, is a plunger 63 including a downwardly directed packing member 64 of leather or the like.

The member 49 is provided with encompassing seats to receive packing rings 65.

Inserted through the partitions 20 and 21 is a tube 66 and extended at one end through the flange 48, and registers with an aperture 67 through the flange.

By this means communication is provided between the compartment 24 and the compartment 22 through the tapered flange 48.

The pipe 18 is received in a hub or boss 68 surrounding the central opening of the member 19 and secured in place by a setscrew 69. The member 18 is formed with a bearing flange 70 between which and the boss 66, a packing 71 is disposed to render the joint air tight.

At its upper end the main discharge 41 is provided with a discharge spout 73 secured to the member 41 by a coupling 74.

Attached to the air escape tube 18 is a support 81 for a standard 82 to which the handle lever 84 is pivoted at 83 and pivoted to the pump rod 38 at 85.

Formed in the inner tapered face of the flange 48 is a vertical channel 79, and formed upon the outer face of the tapered sleeve 49 is a rib 80 to engage in the channel when the member 49 is seated in the member 48, to insure the accurate registration of the aperture 67 with the bore of the tube 66.

Supported by the member 18, or other part of the apparatus is a bracket 81, having a standard 82 rising therefrom, and pivoted at 83 in the standard is a lever 84 coupled at 85 to the pump rod 38, and by means of which the pump rod is actuated.

Supported from the members 18 and 41 is another bracket 86 having a bearing indicated at 87 through which the cutoff rod 59 operates. Rising from the bracket 86 is a standard 88, and pivoted at 89 to the stand-

ard, is a cam device 90 coupled at 91 to the rod 59. By this arrangement the rod 59 may be operated to dispose the valve 60, 61 and 62 either in engagement with the seat 5 of the member 46 or 49, as required.

By this simple arrangement it will be obvious, that the members 27 or 50 and their attachments may be coupled to the casing 19 or removed therefrom as required without the necessity of the operator descending into the pit or well.

I claim:

1. In an apparatus of the class described, a casing divided interiorly into an intake, 15 a gathering and an outlet compartment, said intake and gathering compartments having a communication opening, a discharge conductor leading from said outlet compartment, a conductor adapted to be connected 20 to a pump device and communicating with said intake compartment, a tubular guide communicating with the intake compartment and in vertical alinement with the pump conductor, a pump rod operating 25 through said tubular guide, the casing, and the pump conductor, a plunger attached to said pump rod and operative in said tubular guide, a drainage tube leading from the gathering compartments and having a valve 30 seat within the casing, a tubular guide communicating with the gathering compartment and in alinement with the drainage tube, a tubular shell carried by said last mentioned tubular guide and seated in said casing, said 35 shell having a valve seat spaced from the seat of the drainage tube, a conductor providing communication between said shell and the outlet compartment, a valve operative to alternately engage the spaced valve 40 seats, a rod connected to said valve and leading through the tubular guide, which is associated with the gathering compartment, a plunger attached to said pull rod and operative in the tubular guide which is associated with said drainage tube, and means 45 for actuating said pump rod.

2. In an apparatus of the class described, a casing adapted to be connected to a pump device, a support spaced from the casing 50 and having a plurality of relatively large openings, a discharge conductor connected to said casing and leading through one of the support openings, tubular guide devices for a pump rod and a cutoff rod and 55 connected to the casing and extending through the other of the support openings, and means operative on said support for

detachably clamping said tubular guides to the casing, said guides being removable through the apertures of the support. 60

3. In an apparatus of the class described, a casing adapted to be connected to a pump device, a tubular pump rod guide detachably connected to said casing, a discharge conductor leading from said casing, a tubular guide for a cutoff rod detachably coupled to said casing, a support having a plurality of relatively large openings through which the discharge conductor and the tubular guides extend, and means operative 70 on said support for detachably clamping said guide devices to the support. 75

4. In an apparatus of the class described, a casing having an intake conductor adapted to be connected to a pump device, a tubular pump rod guide detachably engaging said casing, a discharge tube leading from said casing, a drainage conductor leading from said casing and including a valve seat within the casing, a tubular cutoff rod 80 guide detachably engaging said casing, a shell connected to said cutoff rod guide and having a valve seat spaced from the valve seat of the drainage tube, conductor means between said shell and the discharge tube, a valve operative between said seats, a rod connected to said valve, a support, and means operative on the support for clamping the guide devices to the casing. 85

5. In an apparatus of the class described, a casing having an intake conductor adapted to be connected to a pump device, a tubular pump rod guide detachably engaging said casing, a pump rod extending through said pump rod guide, a plunger carried by 90 said pump rod and operative in said pump rod guide, a discharge tube leading from said casing, a drainage conductor leading from said casing and including a valve seat within the casing, a tubular cutoff rod guide detachably engaging said casing, a shell connected to said cutoff rod guide and having a valve seat spaced from the valve seat of the drainage tube, conductor means between said shell and the discharge tube, a valve operative between said seats, a rod connected to said valve, a plunger carried by 95 said cut off rod and operative in said cut off rod guide, a support, and means operative on the support for clamping the 100 guide devices to the casing. 105

In testimony whereof, I affix my signature hereto.

DOMINICK ROHEN.
